OTTO C. F. MEISEL, OF BOSTON, MASSACHUSETTS, ASSIGNOR TO MEISEL PRESS MANUFACTURING COMPANY, OF BOSTON, MASSACHUSETTS, A CORPORATION OF MASSACHUSETTS.

SHEET-HANDLING MECHANISM.

Application filed August 25, 1926. Serial No. 131,368.

This invention relates to sheet-handling mechanism and a primary object thereof is to provide a mechanism which will form from a printed web signatures of folded sheets. 5 In the example of the invention herewith illustrated I have shown a mechanism adapted to form a quarto or eight-page signature comprising two accumulated and folded sheets although it will be understood that the 10 principles of my invention may find embodiment in other forms and that particular mechanisms herein disclosed may be used in other combinations and for other purposes. The arrangement which I am about to describe 15 permits a compact organization capable of rapid and accurate operation.

My invention will be well understood by reference to the following description taken in connection with the accompanying drawings, wherein:

Fig. 1 is a simplified and more or less schematic view showing in side elevation the series of cylinders by means of which the signature is formed;

25 Fig. 1^a is a side elevation of a cam controlling the operation of mechanism associated with the cylinder which appears in Fig. 1 immediately above Fig. 1^a, and is shown as if lifted from its normal position 30 nearer the reader in Fig. and displaced downwardly to the position shown. Part of the cam is broken away to separate the figure from Fig. 1^b.

35 Figs. 1^b and 1^c are similar views showing portions of the cam associated with the cylinder appearing immediately above in Fig. 1. Fig. 1^c is the portion which would be nearer the reader if the cam were in position in Fig. 1. Part of the cam in Fig. 1^c is broken away 40 to separate it from Fig. 1^b.

Fig. 2 is a view on an enlarged scale showing the accumulating cylinder in central section and a cooperating cylinder in end elevation;

45 Fig. 2^a is a section through the cams which are organized at the nearer end of the accumulating cylinder (which appears in Fig. 2 immediately above Fig. 2^a), the section being on the line 2^a—2^a of Fig. 3;

50 Fig. 3 is a section on the line 3—3 of Fig. 2^a;

Fig. 4 is a view on a larger scale showing in section the carrier for a sheet-engaging pin and the means for operating the same; and

Fig. 5 is a view on a similar scale showing the tucker blade in section.

Referring to Fig. 1 of the drawings, I may for purposes of convenience in the description which will follow give brief identifying names to the four aligned and contacting cylinders there shown by which they may be distinguished and in so doing will name them from one of the functions which they perform in the organization illustrated. The cylinder 7 at the left may be termed the cutting knife cylinder and it revolves in contact with the cylinder 9 which may be termed the cutting die cylinder which in turn contacts with accumulating cylinder 11 which opposes paster cylinder 13. These four cylinders may all be geared together, the gearing being not herein shown, to rotate at the same surface speed and conveniently as illustrated the cylinders 7 and 13 are twice the diameter of the cylinders 9 and 11. The mechanism 75 shown is designed to form a signature of two leaves or eight pages, each leaf being of a length equal to the circumference of one of the smaller cylinders 9 and 11, and to fold these leaves centrally to form an eight-page signature, each page being of the width of one-half the circumference of those cylinders.

I will next describe briefly the operation of the parts, referring particularly to Fig. 1. The paper in the form of a printed web leads 85 over the uppermost portion of the cylinder 7 and it is clamped against the cylinder 9 by means of spring-pressed clamping elements 15 carried by cylinder 7 between which operates a knife 17 cooperating with a suitable 90 surface 19 set into roll 9 and which cuts the web across at the bite of the rolls 7 and 9.

As this action takes place with the immediately adjacent parts in the position shown a series of pins 21, projecting in a non-radial or forwardly inclined direction from the cylinder 9 a little to the rear of the cutting point, roll into the edge of the paper at the rear of the cut. The raking or non-radial disposition of the pins is such that the pins 95 enter the paper smoothly with a clean perforation and without danger of tearing. The edge of the paper is entrained by the pins and carried around the lower part of the cylinder 9 until the pins arrive at the 3 o'clock position, at which time similar pins 23 carried by the cylinder 11 roll into and engage 100 the edge of the paper. At this time also the

105

pins 21 are retracted, releasing the paper, the edge of which is carried forward by cylinder 11. After a half revolution of that cylinder the parts of the mechanism are all in the position shown in Fig. 1 of the drawings, the leading edge of the paper being at the 3 o'clock position on cylinder 11 and extending around the upper portion of that cylinder and the lower portion of cylinder 9. At this time the cutting cylinder 7 has made a half revolution and another cutter blade 17 will be brought into opposition to the cylinder 9 and will again sever the web, the portion of the paper which is wrapped around the two cylinders 9 and 11 then forming a single separate sheet, and the pins 21 will engage the paper at the further side of the cut and carry it forward to form the second sheet of the signature.

20 After a half revolution of the cylinder 11 from the position shown the central portion of what has been called the first sheet is brought to the 3 o'clock position opposite paster cylinder 13 and the latter has made a quarter of a revolution counterclockwise and the paster blade 25 will apply paste along the central portion of the sheet to secure the second sheet in position. This paster blade may be mounted to reciprocate radially in cylinder 13, being operated by a cam roll 27 running on a stationary eccentric 29 which operates to move the blade 25 outwardly substantially in the 3 o'clock position to receive paste from paste roll 31.

35 After a complete revolution of cylinder 11 from the position shown the pins 23 will receive the leading edge of the second sheet from the pins 21 which are retracted to deliver the same and this second sheet is severed as the pins 23 again approach the 3 o'clock position. Then as the pins 23 come to about the 6 o'clock position they are retracted from the paper and suitable stripper means, presently to be described, may be operated to release the leading portion of the paper from the cylinder. It remains, however, clamped between the cylinders 11 and 13 until the central portion of the two sheets arrives at the center line between these two cylinders, at which time a tucker blade 33 carried by cylinder 11 is projected outwardly into cooperation with suitable female folding mechanism 35 carried on cylinder 13 to fold the two sheets centrally into the form of a signature. This folded signature is then carried downwardly gripped by mechanism 35 to a feed roll 37 and is removed from cylinder 13 by the strippers 39 working in grooves in the cylinder and passes to suitable collecting mechanism of any desired kind.

40 I will next describe the construction of a pin and its carrier and thereafter the method of operating the same and for convenience I will describe the mechanism of one of the pins 21 which are associated with the cylinder 9.

Referring to Fig. 4, each pin 21, which may be a suitable length of piano wire and of which a suitable number are disposed in alignment along the length of the cylinder as will be well understood, is mounted in a carrier in the form of a rod 41, the outer end of which slides in a cup or sleeve 43 inset in the face of the cylinder and secured by a screw 45, the pin 21 passing through a screw 47 tapped into the end of the rod which serves as a chuck to hold the pin, the outer end of the pin projecting as shown through a suitable hole in the bottom of the cup 43. The screw holds the pin tightly but the latter may nevertheless be manually adjusted, conveniently when the screw is withdrawn. As shown, the rod 41 may be bored to receive the surplus length of pin at the rear. The inner end of the rod 41 may be supported and guided by a collar 49 pinned thereto and sliding in the opening 51 in the cylinder which receives the rod, this collar also forming a bearing for one end of the compression spring 53 which is interposed between this collar and the end of sleeve 43 and which normally tends to draw the rod to the right in the figure and retract pin 21 to a position within the circumference of cylinder 9. To operate the pins against the force of the springs 53 to hold the same in projected position to engage the paper the inner ends of the set of rods may be wiped or cammed by the rounded inner end of a plunger bar 55 which reciprocates radially in the cylinder. This bar is normally thrust outwardly by the action of springs 56 (see Fig. 4) under the ends of the bar, but may be moved inwardly toward the left in the figure to move the pin to the position there shown by the action of suitable cams organized at the ends of the cylinder and cooperating with cam rolls 57 on the ends of the bar 55.

45 Referring now to Figs. 1 and 1^a of the drawings, I have shown in Fig. 1^a the cam 59 which cooperates with the roll 57 shown in Fig. 1. This cam is illustrated as if Fig. 1^a and Fig. 1 were sections on parallel planes through the completed mechanism. Cam 59 herein takes the form of a stationary disc surrounding the shaft 61 of cylinder 9 and having on its inner face a cam track 63 cooperating with follower 57 and having a depressed portion 65 of increased radius so positioned as to permit the outward movement of the follower 57 as pin 21 reaches the 3 o'clock position. The springs 53 may then act to retract the pins 21 from the paper, permitting the paper to be engaged by the pins 23 and carried away by the cylinder 11.

50 The pins 23 may be similarly mounted and may be operated by a plunger 67 similar to the plunger 55 and having cam followers 69 for controlling the same. The pins 23, however, should not be retracted upon each revolution of the cylinder but only on periodic revolutions, in the present instance, since two

sheets are to be accumulated, on every second revolution. To permit this operation I may utilize a two part cam as shown in Figs. 1^b and 1^c and also in Figs. 2^a and 3. Referring to these figures, the cam may embody a stationary portion 71 organized about the shaft 73 of cylinder 11 and having an internal cam track 75 shown in full lines in Fig. 2 having a depressed portion 77 analogous to that of the cam 59 but in the 3 o'clock position. The cam 71 also provides a bearing for the sleeve-like flange 79 on a second cam having an internal cam face 81 having a circular portion of the same radius as the circular portion 15 of cam face 75 but a portion of greater radius, as illustrated in full lines in Fig. 1^c and in dotted lines in Fig. 2^a, for about a quarter of its extent. The sleeve-like flange of cam 79 may be provided with shrouded gear teeth 20 83 and is adapted to be driven by a gear 85 to rotate in the opposite direction to the cylinder 11 and at one-half the speed. When the parts are in the position shown in Fig. 1 and the leading end of the first sheet is engaged by 25 the pins 23 the two parts of the controlling cam are in the position shown in Fig. 1^b and the depressed portion of each cam track is masked by the circular portion of the other and the cam roll 69 is held in inward position. 30 After a revolution of the cylinder 11 clockwise and a half revolution of cam 79 counterclockwise the portion of the cam track 81 of greater radius is brought opposite the depressed portion 77 of the stationary cam track 75 as seen in Fig. 2^a and cam roll 69, as seen above in Fig. 2, is released to the latter, permitting the retraction of the pins 23. 35 Concurrently with the retraction of pins 23 suitable stripper mechanism carried by the cylinder 11 may be operated to free the sheet and herein I have shown such stripper mechanism as operated by the plunger 67. Referring to Fig. 2, I have herein shown a rock shaft 87 carried by cylinder 11 rearwardly of the position of the pins 23 and to this rock shaft are fixed long fingers 89, the ends of which extend forwardly past the position of the pins and which are normally housed in suitable recesses 91 in the cylinder. If rock 45 shaft 87 is rotated, these fingers 89 will be lifted, as illustrated in Fig. 2, to strip the paper from the pins and lift it from the surface of cylinder 11 as will be well understood. For this purpose the rock shaft 87 may be 50 provided with gear teeth forming a segment cooperating with gear teeth on a shaft 93 journaled in the cylinder, from which shaft there extends inwardly an arm 95, the inner end of which acts on a stud 97 extending inwardly from the wiper plunger 67 so that when the latter is released by the cams to be 55 pressed outwardly by its springs (similar to springs 56 of bar 55 as shown in Fig. 4) the stud 97 will draw on arm 95 and rock shaft 60 87 to the position shown in Fig. 2, raising the

stripper fingers 89 which are there shown in their extreme position.

To insure the disengagement of the paper from the cylinder 11 (see Fig. 1) suitable stripper fingers 99 may be mounted on a rock shaft 101 adjacent the cylinder 11. At a suitable time as the edges of the sheets, which are to be disengaged from the cylinder, approach, these fingers will be swung upwardly into proximity to the cylinder so as to engage under the edges of the sheets lifted by fingers 89 to strip the sheets from the cylinder to the supporting surface beneath. The rock shaft 101 may be operated at a suitable time by means of the crank arm 103 secured by connecting rod 105 to rocker link 107 having a cam follower 109 which cooperates with a suitable cam 111 rotating with cutter cylinder 7. 75 80

Referring again to Fig. 2, as the clockwise rotation of cylinder 11 continues, the cam rolls 113 of the tucker blade mechanism are released to the depressed portion of the cams, permitting the tucker blade 33 to be thrust outwardly and to fold the paper between the fixed surface 115 and the movable clamp bar 117 of the cooperating mechanism carried by cylinder 13 and as the blade passes the 3 o'clock position, which is its position of greatest extension, and the folding is completed it is again retracted to free the same. 90 95

While the tucker blade mechanism might take various suitable forms, I may utilize that claimed in my divisional application, Serial No. 241,371, filed Dec. 20, 1927, and shown in detail in Fig. 5 wherein I have 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 shown to provide a clearance so that the tucker blade 33 may roll into position and is closed as it reaches the 9 o'clock position corresponding to the full extension of the tucker blade, thus providing for the folding or creasing of the signature. Movement of the blade 117 is herein shown as effected by means of a cam, shown in Fig. 2 but omitted from Fig. 1, which operates on a follower 131 5 on an arm 133 carried by shaft 129 and adapted to swing said arm counterclockwise against the action of spring 135. The cam is herein shown as having a toe or rise 137 secured to a stationary disc 139. This rise portion may 10 conveniently be formed of a section of a flanged ring having a cylindrical flange portion from which is formed the toe of the cam and an annular base portion the segment 141 of which may lie against the side of disc 139 15 and be adjustably bolted thereto in the manner indicated in the figure.

I have not attempted to show in the drawings the relation of the parts transversely of the machine but it will be well understood 20 that various of the cooperating parts, as, for instance, the pins 21 and the pins 23, are placed out of alignment in different planes and that suitable clearance slots or grooves are provided in the various cylinders or parts 25 to permit the passage of elements carried by an adjacent cylinder, as is customary in the art.

I have described in detail the construction 30 illustrated in order that it might be well understood and without definitive or limiting intention. What I claim as new and desire 35 to secure by Letters Patent I shall express in the following claims.

I claim—

- 40 1. In a sheet handling mechanism a cylinder having a reciprocating pin-carrying rod therein and a plunger movable towards and from the center line of the cylinder having a surface acting against said rod to move the same and a cam for controlling the position of the plunger relative to such center line.
- 45 2. In a sheet handling mechanism a cylinder having a pin-carrying rod reciprocating therein, a radial plunger having a surface acting on the inner end of the rod to move the same, a cam follower on the plunger and an annular cam surface at the end of the cylinder cooperating with the follower.
- 50 3. In a sheet handling mechanism a cylinder having movable sheet-engaging pins at the surface thereof and mechanism for operating the pins to engage or release the sheet received within the body of the cylinder and having an actuating cam follower presented at the end thereof and an annular cam at the end of the cylinder.
- 55 4. In a sheet handling mechanism the combination of pin carriers disposed non-radially in the cylinder, pins carried thereby, the carriers being movable substantially axially

of the pins, springs tending to move the carriers in one direction, means to move them against the springs comprising a plunger movable substantially radially in the cylinder and adapted to wipe the carriers and a cam 70 controlling the plunger.

5. In a sheet handling mechanism a cylinder having reciprocable pins to engage the leading edge of the sheet, a rock shaft carried by the cylinder rearwardly of the pins having arms to lift the paper away therefrom, means to effect reciprocation of the pins and means actuated thereby to turn the shaft. 75

6. In a sheet handling mechanism a cylinder having reciprocable pins to engage the leading edge of the sheet, a rock shaft carried by the cylinder rearwardly of the pins having arms to lift the paper away therefrom, means to effect reciprocation of the pins and means actuated thereby to turn the shaft 80 85 comprising a connection within the body of the cylinder.

7. In a sheet handling mechanism a cylinder having sheet-engaging pins at the surface thereof, carriers for the pins, a plunger in the cylinder to act on said carriers, a stripper at the surface of the cylinder and a connection to said plunger to lift the stripper on movement of the former incident to withdrawal of the pins. 90

8. In a sheet handling mechanism a cylinder having sheet-engaging pins at the surface thereof, carriers for the pins, a plunger in the cylinder to act on said carriers, a rock shaft at the surface of the cylinder having arms to engage the paper, a lever extending inwardly to rock the shaft and a connection between the lever and the plunger to lift the arms on movement of the former incident to withdrawal of the pins. 95

9. In a sheet handling mechanism a cylinder having sheet-engaging pins at the surface thereof, carriers for the pins, a plunger in the cylinder to act on said carriers, a rock shaft at the surface of the cylinder having arms to lift the paper, teeth carried by the shaft, a pinion element engaging the teeth having a lever extending inwardly therefrom and connected to the plunger to be swung thereby on movement of the same incident to withdrawal of the pins whereby to rock the shaft and lift the paper by means of said arms. 100 110 115

10. In a sheet handling mechanism a cylinder having sheet-engaging pins at the surface thereof, a reciprocating tucker-blade working therein, means controlling the movement of pins and blade comprising substantially radially movable followers at the end of the cylinder and an annular cam adjacent 120 125 the end of the cylinder cooperating therewith.

11. In a sheet handling mechanism a cylinder having sheet-engaging pins at the surface thereof, a reciprocating tucker-blade 130

working therein, means controlling the movement of pins and blade comprising substantially radially movable followers at the end of the cylinder and a pair of annular cams

5 at the end of the cylinder each having a depressed portion and means for revolving one of the cams relatively to the other whereby the followers are released to the conjoint action of said depressed portions on periodic 10 revolutions only of the cylinder.

12. In a sheet handling mechanism a cylinder having movable sheet engaging pins at the surface thereof and mechanism for operating the pins to engage or release the sheet 15 received within the body of the cylinder having an actuating cam follower presented at the end thereof, annular cams at the end of the cylinder, each having a depressed portion, and means for revolving one of said cams

20 relatively to the other whereby the follower is released to the conjoint action of said depressed portions on periodic revolutions only of the cylinder.

13. In a sheet handling mechanism in combination with a cylinder having pins to pierce the paper adjacent its leading edge, stripper means comprising fingers pivoted rearwardly of said pins and extending forwardly about the circumference of the cylinder and beyond 30 said pins.

14. In a sheet handling mechanism in combination with a cylinder having pins to pierce the paper adjacent its leading edge, stripper means comprising fingers pivoted rearwardly 35 of said pins and extending forwardly about the circumference of the cylinder and beyond the pins, means to retract the pins and means governed thereby to lift the fingers.

15. In a sheet handling mechanism an accumulating cylinder having means successively to engage a number of sheets at the leading edges thereof and governed to release the

same on periodic revolutions and a tucker-blade housed in the cylinder and adapted to be projected therefrom to fold the released 45 accumulated sheets.

16. In a sheet handling mechanism an accumulating cylinder having means successively to engage a number of sheets at the leading edges thereof and governed to release the 50

same on periodic revolutions, a tucker-blade housed in the cylinder and adapted to be projected therefrom to fold the released accumulated sheets and a stripper carried by the cylinder between said engaging means and 55 blade to engage the underside of the sheets and raise the leading portion thereof from the cylinder to facilitate the action of said blade.

17. In a sheet handling mechanism a cylinder having means to engage a sheet at its leading edge, means to disengage the same, a tucker-blade housed in the cylinder and adapted to be projected therefrom to fold the sheet and a stripper carried by the cylinder 60 between said engaging means and said blade to engage the underside of the sheet and raise the leading portion thereof from the cylinder to facilitate the action of said blade.

18. The pin carrier comprising a rod, 70 means to clamp a pin substantially axially at the end of the rod, a sleeve forming a bearing for one end of the rod, a collar forming another bearing therefor and a spring between sleeve and collar.

19. The pin carrier comprising a rod having a substantially axial recess to receive the pin, a screw tapping therein through which the pin passes and by which it is held and means associated with the rod by which it 75 may be reciprocated.

In testimony whereof, I have signed my name to this specification.

OTTO C. F. MEISEL.
